UNITED STATES PATENT OFFICE.

JULIUS M. REIS, OF NEW YORK, N. Y.

EMBROIDERY.

1,189,384.

Specification of Letters Patent.

Patented July 4, 1916.

Application filed March 1, 1913. Serial No. 751,486.

To all whom it may concern:

Be it known that I, JULIUS M. REIS, a citizen of the United States, and a resident of New York, county of New York, and 5 State of New York, have invented certain new and useful Improvements Relating to Embroidery, of which the following is a specification.

My invention relates to an article of 10 manufacture, and particularly to an article of dry goods, for instance, wearing apparel in combination with an embroidery foundation and filling thereon, to be marketed with the embroidery design and filling thereon, 15 and later to be embroidered by the purchaser.

One further feature of my invention is to 20 color the foundations especially with varying shades of color so as to indicate desirable colors of embroidery thread to be used in embroidering over the foundations.

Heretofore it has been customary to market some articles of dry goods, which have been stamped in ink or the like, with certain 25 ornamental designs so that the purchaser may embroider the article according to the design. In such case, however, in order to give the embroidery the necessary body, filling material must be used, over which the 30 embroidery is performed. This method is subject to many disadvantages. It is extremely difficult for the average purchaser to hold the filling material in proper position while embroidering thereover, which 35 not only causes very poor results but the operation takes a very long time, and the two together tend to discourage the public from embroidering generally.

In the drawings, Figure 1 illustrates a 40 garment embodying my invention in one form; Fig. 2 is a section through a portion of the same taken on the line II-II of Fig. 1; and Figs. 3 and 4 are enlarged views of the colored foundations.

45 Referring to the drawings, 3 represents a garment or article of wearing apparel of cloth, the edges 4 of which are left raw. Secured to the cloth near these edges are strips of cellulosic material 5, preferably 50 paper pulp or the like, in the form of scallops, as clearly shown in Fig. 1. The strips 5 are firmly secured to the cloth by means of an adhesive for instance a cement 6 (Fig. 2) which is preferably composed of 55 rubber dissolved in carbon disulfid. The improved method of applying these paper

pulp foundations to the articles is to first spray one side of a sheet of paper pulp with the cement, then stamp or cut out the foundations, then spray the opposite side 60 with the various colors, and then apply them to the article by the aid of forms, with the adhesive side against the cloth, and then allow the cement to dry or harden 65 by evaporation of the solvent or softening liquid. The drying may be hastened by applying heat, as by applying a hot iron to the foundations. The cement causes the foundations to adhere firmly to the cloth so that they will not become detached by shipping or even the roughest handling. Other 70 ornamental paper pulp foundations may be applied in the same manner to the article, as at 7, 8, 9 and 10. When the purchaser receives the article, in order to produce a 75 finished embroidered article it is only necessary to embroider over the paper pulp foundations which serve the double purpose of patterns and filling material.

By the use of my improvements, the raw 80 edges of the cloth may be cut off to conform to the scallops before embroidering, which has been practically impossible with prior arrangements.

Not only does the coloring of the foundations indicate the desirable colors with 85 which the article is to be embroidered, but when so embroidered, should the embroidery threads become separated in any manner on the top of the foundations, a 90 color will show through which is substantially of the same color as the embroidery thread so that the gap will not be noticeable. If for instance, a white foundation 95 were embroidered with black or blue thread, and a gap should occur at any point, the artistic effect would be ruined by the appearance of white through the gap, but this disadvantage is entirely overcome in my invention. By shading the color or colors on 100 a foundation from light to dark, (Fig. 3) or from one color to another, as indicated in Fig. 4, the most desirable artistic effects 105 can be indicated and any gap in the embroidery threads will not materially disfigure the embroidery.

The new article is obviously far more 110 advantageous than those heretofore on the market, which merely have thereon the design stamped in ink or the like, in that the purchaser is saved the time, trouble and expense of purchasing separate filling ma-

terial and the great trouble and time getting it and keeping it properly in place, with the result that many articles are so poor or defective in the embroidering that they 5 must be either partly or wholly done over, or else are not fit for the uses for which they were originally intended. The spraying of the adhesive cement on the foundations causes the latter to receive an even 10 coat of adhesive in a short time before the liquid solvent has time to materially evaporate, and the spraying of the exposed face of the foundations with coloring material after the forms are cut permits a great 15 variety of colors on the same or different forms, with only a small stock of forms.

Although I have described my improvements in great detail and with respect to a specific embodiment thereof, I do not desire 20 to be limited to such details, except as clearly pointed out in the appended claims, as many changes and modifications may be made without departing from the spirit and scope of the invention in its broader aspects, 25 and I consequently desire to cover all arrangements coming within the scope of any one or more of the appended claims.

What I claim as new and desire to secure by Letters Patent is:

30 1. An article of dry goods, comprising a cloth article to be marketed, having an embroidery foundation of cellulosic material firmly secured thereto by an adhesive, the exposed face of the foundation being colored, whereby the foundation serves as a 35 pattern for the embroidery, as a filling material therefor, and as a chart for selecting the embroidery colors, and whereby a gap in the embroidery threads will not materially disfigure the embroidery.

40 2. An article of dry goods, comprising a cloth article, having an embroidery founda-

tion of cellulosic material secured firmly thereto by an adhesive, said foundation serving both as a pattern for the embroidery and as a filling material therefor. 45

3. The improved embroidery foundation comprising a form of cellulosic material, one side thereof being colored with colors shading from one color or shade to another, whereby the foundations, serve as patterns for the embroidery, as a filling material therefor, and as a chart for selecting the embroidery colors, and whereby a gap in the embroidery threads will not materially 50 disfigure the embroidery. 55

4. The improved embroidery foundation, comprising a suitable filler form shaped according to the form of the embroidery and colored according to the colors to be used 60 in embroidering thereon, whereby the foundation serves as a pattern for the embroidery, as a filling material therefor and as a chart for selecting the embroidery colors, and whereby a gap in the embroidery 65 threads will not materially disfigure the embroidery.

5. An article of dry goods comprising a cloth article to be marketed, having an embroidery filler form thereon colored according to the colors to be used in the embroidery, whereby the form serves as a pattern for the embroidery, as a filling material therefor and as a chart for selecting the embroidery colors, and whereby a gap 70 in the embroidery threads will not materially disfigure the embroidery. 75

In testimony whereof, I have signed my name to this specification, in the presence of two subscribing witnesses.

JULIUS M. REIS.
